*Primary Examiner—Stella Reid**Assistant Examiner—Selina Sikder*(74) *Attorney, Agent, or Firm—Carter, DeLuca, Farrell & Schmidt, LLP*(57) **CLAIM**

The ornamental design for a decorative rocker switch, as shown and described.

DESCRIPTION

FIG. 1 is a perspective view of a decorative rocker switch having a planar window panel;

FIG. 2 is a top view of the decorative rocker switch of FIG. 1;

FIG. 3 is a bottom view of the decorative rocker switch of FIG. 1;

FIG. 4 is a side view of the decorative rocker switch of FIG. 1, the other side view being the same;

FIG. 5 is a top end view of the decorative rocker switch of FIG. 1, the bottom end view being the same; and,

FIG. 6 is a perspective view of the decorative rocker switch of FIG. 1 showing an intended environment in phantom.

The broken line showing of the environment is for illustrative purposes only and form no part of the claimed design.
